REMOVABLE GARMENT PAD

Osa E. Jay and Elaine Gildersleeve,
Washington, D. C.

Application October 30, 1945, Serial No. 625,468

6 Claims. (CL 2-268)

1

This invention relates to a removable garment pad and has for one of its objects the production of a simple and efficient garment pad wherein the pad itself is removable from a casing, which casing is fixed to the garment, thereby facilitating the cleaning of the garment and casing while the pad is removed to prevent injury to the pad.

A further object of this invention is the production of a simple and efficient shoulder pad construction having a casing within which a removable pad is placed and held in position without employing stitching or other auxiliary anchoring means for the pad.

Other objects and advantages of the present invention will appear throughout the following specification and claims.

In the drawing:

Figure 1 is a fragmentary front elevational view of the shoulder and sleeve portion of a garment showing the pad in position, certain parts being shown in section;

Figure 2 is an enlarged fragmentary sectional view taken on line 2-2 of Figure 1;

Figure 3 is a perspective view of the pad and casing in assembled relation;

Figure 4 is a top plan view of the pad and casing, certain parts being shown in section;

Figure 5 is a longitudinal sectional view taken on line 5-5 of Figure 4;

Figure 6 is a top plan view of the pad removed from the casing;

Figure 7 is a transverse sectional view taken on line 7-7 of Figure 4, the pad being shown partly in end elevation;

Figure 8 is a perspective view of the casing, the pad being shown in dotted lines and folded for insertion into the casing;

Figure 9 is a longitudinal sectional view through the shoulder portion and sleeve of a garment illustrating the manner of stitching the casing to the garment for removably supporting the pad which pad is shown in position within the casing;

Figure 10 is a similar sectional view with the pad removed;

Figure 11 is a sectional view similar to Figure 1, illustrating the position of the pad when extending in a sleeve-supporting position.

By referring to the drawing, it will be seen that 10 designates the shoulder portion of a garment to which the sleeve 11 is secured in the conventional manner. The present invention consists of a casing 12 which is adapted to be secured to the garment in a selected manner, and a re- 55

2

movable pad 13 which is supported within the casing 12. The casing 12 is preferably triangular in shape, as shown, and is formed to provide an envelope, the rear edge of which is stitched together to provide a projecting seam 14. The casing 12 tapers toward its front edge and is provided with a restricted pad-receiving opening 15. The casing 12 is selectively secured to the garment in the manner shown in Figure 1 to extend over the shoulder away from the sleeve, or as that shown in Figure 11 to extend into the top of the sleeve away from the shoulder. The sides of the casing 12 diverge outwardly toward the rear seam 14 thereby providing a tapering pocket into which the triangular pad 13 fits. The seam 14 is preferably stitched to one part of the seam which joins the sleeve to the garment to extend the casing 12 selectively under the shoulder portion or into the sleeve of the garment. The casing 12 is also tacked, as at 16, to the shoulder portion of the garment when in the position shown in Figure 1, or is tacked, as at 18 to the sleeve 11 when in the position shown in Figure 11, so as to anchor the casing 12 near its opening.

The triangular pad 13 is preferably stitched, as at 17, around its edges and transversely, as at 18, adjacent its apex 19 to hold the padding material in place and prevent this material from crowding toward one corner of the pad 13. The pad 13 may be inserted into the casing 12 through the opening 15 in any desired manner, either by folding the ends of the pad under in the manner shown in dotted lines in Figure 8, or by inserting one corner through the opening 15 and crumpling the pad so as to reduce its area to a size to fit through the opening 15. After the pad 13 has been inserted into the casing 12, the pad is straightened out to lie flat and snugly within the casing 12 in a manner shown in Figure 4.

The tapering shape of the pad 13 fitting within the tapering casing 12 will cause the pad 13 to be retained within the casing 12, since only the apex 19 of the pad 13 will protrude through the restricted opening 15 and beyond the end of the casing 12. Since the casing 12 is stitched to the garment, the casing 12 will remain attached to the garment while it is being laundered or cleaned. The pad 13 is removed from the casing 12 simply by pulling the pad 13 through the opening 15 out of the casing 12. The pad 13 may be replaced within casing 12 after the garment has been cleaned, and in this way the garment is ready for wear without the necessity of stitching or otherwise anchoring the pad in position.

It should be understood that the casing 12 and the pad 13 may be changed as to shape, or design, without departing from the spirit of the invention so long as these changes fall within the scope of the appended claims. One form or design has been illustrated and one important feature is the casing 12 which is provided to be permanently attached to the garment for supporting a removable flexible pad 13, which pad is retained within the casing 12 because of the restricted opening 15, and because of the tapering shape of the pad and casing. It has been found quite important to cut the material forming the casing 12 so that the longitudinal threads will run parallel to the shoulder seam of the garment when attached thereto to prevent the casing from twisting while laundering, and more particularly to cause the casing and pad to conform to the contour of the shoulder and to hold the casing in its proper place—see Figure 4. The cloth of the pad 13 is so cut as to cause the longitudinal or warp threads to extend diagonally or on the bias to facilitate the insertion of the pad into the casing.

From the foregoing description it will be seen that a very simple and efficient removable garment pad has been produced wherein the casing or envelope is fixed to the garment and may be laundered with the garment. The removable pad 13 is so constructed as to be easily and quickly removed from or inserted into the casing or envelope 12. The pad 13 may be easily folded, rolled, or flexed to be inserted into the opening 15 and to be pulled easily and quickly through the opening from the casing. Because of this structure the garment when laundered or cleaned may quickly dry and may be quickly and efficiently ironed without interference by the pad due to a bulky structure since the pad is removed and may be quickly and easily replaced. The casing will shield the pad from contact with the body of the wearer over a major portion of the length of the pad and if it is desired to launder the pad, this may be done separately.

It should be noted that the pad is of substantially the same configuration as the casing and fits snugly within the casing when lying flat therein, a portion of the pad projecting beyond and through the restricted opening which is formed in the casing.

Having described the invention, what is claimed as new is:

1. A shoulder pad for garments comprising a flexible pad member, a pad member-containing casing having a wide portion and a relatively narrow portion, the relatively narrow portion being spaced from said wide portion, said relatively narrow portion having a pad member-receiving and ejecting opening, the opening being smaller than said pad member, the pad member being insertable when flexed through the opening and the pad member being removable through said opening when the pad member is flexed, the pad member being adapted to normally lie flat and snug in said casing, and the narrow portion of the casing constituting means to hold the pad member against accidental removal from said casing while lying flat in said casing.

2. A shoulder pad for garments comprising a triangular casing having a closed wide portion and a narrow forward portion, the narrow portion having a narrow restricted opening therein of less width than the wide portion, a removable flexible pad member mounted within said casing

and having a wide portion and a narrow restricted portion, the pad member when flexed being insertable through said restricted opening and lying flat and fitting snugly within said casing when inserted in said casing, the wide portion of the pad member being wider than the restricted opening of the casing thereby providing means for holding the pad member against accidental removal from said casing while at the same time being forcibly removable through said opening when the pad member is flexed.

3. A shoulder pad for garments comprising a casing having a closed wide portion and a narrow forward portion, the narrow portion having a narrow restricted opening therein of less width than the wide portion, a removable flexible pad member mounted within said casing and having a wide portion and a narrow restricted portion, the pad member when flexed being insertable through said restricted opening and lying flat and fitting snugly within said casing when inserted in said casing, the wide portion of the pad member being wider than the restricted opening of the casing thereby providing means for holding the pad member against accidental removal from said casing while at the same time being forcibly removable through said opening when the pad member is flexed.

4. An article of the class described comprising a triangularly-shaped casing having converging side portions, the casing having a transversely-extending restricted opening located inwardly of the normal apex of the converging side portions, the casing having a rear portion of greater width than the restricted opening, the side portions diverging toward said rear portion of greater transverse width than the transversely-extending restricted opening, and a triangularly-shaped removable pad member fitted into said casing through said restricted opening, the pad member having side portions converging toward the restricted opening and diverging toward the rear portion, the side portions of the pad member fitting snugly against the side portions of the casing within the casing to support the pad member within the casing against accidental removal from the casing when the pad member is carried in the casing.

5. An article of the class described comprising a triangularly-shaped casing having converging side portions, the casing having a transversely-extending restricted opening located inwardly of the normal apex of the converging side portions, the casing having a rear portion of greater width than the restricted opening, the side portions diverging toward said rear portion of greater transverse width than the transversely-extending restricted opening, and a triangularly-shaped removable pad member fitted into said casing through said restricted opening, the pad member having side portions converging toward the restricted opening and diverging toward the rear portion, the side portions of the pad member fitting snugly against the side portions of the casing within the casing to support the pad member within the casing against accidental removal from the casing when the pad member is carried in the casing, the pad member and casing being flexible in a manner whereby the rear portion of the pad member may be folded back upon the pad member to reduce the transverse area of the pad member to facilitate the removal of the pad member from said casing through the restricted opening of the casing.

6. An article of the class described comprising

a triangularly-shaped casing having converging side portions, the casing having a transversely-extending restricted opening located inwardly of the normal apex of the converging side portions, the casing having a rear portion of greater width than the restricted opening, the side portions diverging toward said rear portion of greater transverse width than the transversely-extending restricted opening, and a triangularly-shaped removable pad member fitted into said casing through said restricted opening, the pad member having side portions converging toward the restricted opening and diverging toward the rear portion, the side portions of the pad member fitting snugly against the side portions of the casing within the casing to support the pad member within the casing against accidental removal from the casing when the pad member is carried in the casing, the pad member and casing being flexible in a manner whereby the rear portion of the pad member may be folded back upon

the pad member to reduce the transverse area of the pad member to facilitate the removal of the pad member from said casing through the restricted opening of the casing, the pad member having a pointed apex normally projecting through the restricted opening of the casing when the pad member and casing are assembled.
